(57) **CLAIM**

The ornamental design for a timing chain guide, as shown and described.

DESCRIPTION

FIG. 1 is a front perspective view of a timing chain guide in accordance with the present invention;
FIG. 2 is another front perspective view thereof;
FIG. 3 is a rear perspective view thereof;
FIG. 4 is another rear perspective view thereof;
FIG. 5 is a rear elevation view thereof;
FIG. 6 is front elevation view thereof;
FIG. 7 is an end elevation view thereof;
FIG. 8 is an opposite end elevation view thereof;
FIG. 9 is a top plan view thereof; and,
FIG. 10 is a bottom plan view thereof.

1 Claim, 3 Drawing Sheets
